UNITED STATES PATENT OFFICE.

JOSEF SVEICH, OF POPOVIČKY, AUSTRIA-HUNGARY.

ROTARY MACHINE.

No. 926,301.

Specification of Letters Patent.

Patented June 29, 1909.

Application filed February 5, 1909. Serial No. 476,263.

To all whom it may concern:

Be it known that I, JOSEF SVEICH, a subject of the Emperor of Austria, residing at Popovičky, in the Kingdom of Bohemia and 5 Austrian Monarchy, have invented a new and useful Improvement in Rotary Machines, of which the following is a specification.

My invention relates to improvements in machines having one eccentrical rotary piston 10 ton, which rotates in its cylindrical casing so as to remain in a continual contact with it in a straight line, while the space between cylinder and piston is divided in two partitions or chambers by a sliding abutment, which 15 moves out of the way of the piston to let it pass; and the objects of my improvements are, first, to maintain a sufficiently tight contact between the sliding abutment and the surface of the cylinder; second, to make the 20 pressure of the sliding abutment upon the cylinder continually elastic; third, to attain sufficient durability for the good working of the sliding abutment of said machine. I attain these objects by the mechanism illustrated in the accompanying drawing, in 25 which—

Figure 1 is a vertical section of the machine, having an oval piston, and in Fig. 2 the same having a circular piston; Fig. 3 a 30 side elevation of the machine.

3 is the cylinder having the shaft 1 passing centrally through it. The piston 2 is simply an eccentric cylinder of oval or circular section, fast on the shaft, and working in contact with the cylinder 3 of the casing at one straight line, which is parallel to the axis. The induction port 4 and the eduction port 5 are placed to the right and to the left of the sliding plate 6 which is guided by its casing 7 35 in central direction against the piston 2. I construct it preferably direct over the axis 1, so that it reposes by its weight upon the rotary piston. Volute springs, or one volute spring 9 only, sitting on a stile 8 which is 40 fastened on said sliding plate 6 in the middle and in a central direction, is pressing it con-

tinually against the piston. If several such volute springs are pressing at once, they must be divided symmetrically upon the whole length of the slide, so as to produce a 50 pressure which acts regularly and with the same force at each point of the contact line between the sliding abutment and the cylinder. The volute spring is inclosed between a plate 10 upon the stile and between the cover 55 12 by which the casing 11 of the volute spring is closed. The casing 11 is firmly fastened upon the casing of the machine. By this arrangement the contact of the sliding abutment and the piston is continual and an elastic contact accompanied by a mutual soft grinding between the sliding abutment and the rotary piston is produced, whether the piston rotates or not. The effect of it will be 60 a durable tight contact between the cylinder 65 and the sliding abutment.

I do not claim said rotary machines broadly, whether they may be used as engines or pumps, blowers, motors, or in any other way, but

What I do claim as my invention, and desire to secure by Letters Patent, is:

A rotary pump for engines comprising in combination, a stationary member having a cylinder and an inlet and outlet passage communicating therewith and a vertically disposed guiding member in alinement with the center of said cylinder and projecting between said passages through the perimeter of said cylinder, a rotary piston eccentrically 75 mounted in said cylinder, a downwardly acting vane member disposed in said guiding portions and engaging said piston, a piston spring, and a spring casing secured to said cylinder for holding said spring in engagement with said piston.

In testimony whereof I affix my signature in presence of two witnesses.

JOSEF SVEICH.
